UNITED STATES PATENT OFFICE.

WILLIAM J. MERTEN, OF PITTSBURGH, PENNSYLVANIA.

CASEHARDENING.

Application filed December 2, 1920. Serial No. 427,753.

To all whom it may concern:

Be it known that I, WILLIAM J. MERTEN, a citizen of the United States, and a resident of Pittsburgh, in the county of Allegheny and State of Pennsylvania, have invented a new and useful Improvement in Casehardening, of which the following is a specification.

This invention relates to case hardening, more particularly to a method of case hardening which is adapted to rapidly and uniformly case harden metal articles, even of complex form, and an apparatus for practicing my new method.

Hitherto, several methods have been proposed for case hardening of steel parts among which the one in general use was a method in which the articles to be hardened were packed with carburizing materials in a metal box, after which the box was tightly sealed to prevent access of air. The material was then heated to a relatively high temperature for a considerable length of time.

The results obtained in this operation were uncertain and it was difficult to duplicate a predetermined result because of the non-uniformity of the carburizer and the fact that the heat to which the steel was exposed could not be readily controlled, owing to the parts being treated being but indirectly exposed to the heat. The cost of heating was high and the metal boxes in which the articles were sealed rapidly deteriorated due to oxidation or scaling.

Another method consisted in immersing an article to be hardened in a cyanide bath heated to a rather high temperature. This method was fairly effective with small articles where only surface hardening was desired but was objectionable in that a uniform case hardening could not be produced and the articles immersed in various parts of the bath were unequally penetrated.

Often the article was heated to a high temperature and then plunged into a container filled with powdered cyanide, or such powdered salt was sprinkled on the hot metal article. This method produced a case which was very superficial and had but little resistance to wear.

My invention obviates the disadvantages of the prior processes, it being among the objects thereof to devise a method wherein the article to be treated is uniformly case

hardened in a very simple and efficient manner.

In practicing my invention, I provide a source of a suitable gaseous material, such as cyanogen gases, which are allowed to come in contact with the article to be treated at an elevated temperature, whereby the article absorbs the gases uniformly, forming a uniform case thereon. In order to conserve the cyanogen gases which are relatively expensive, I have devised an apparatus in which such gases are returned to the system, after coming in contact with the article.

In this manner, I am enabled to utilize, to the fullest extent, the cyanogen gases which have long been recognized as being a very efficient carburizing medium; I obtain a case of greater uniformity and deeper penetration than with the use of other methods and I also avoid the disadvantages inherent in the use of a poisonous substance, such as cyanogen.

In the accompanying drawings forming a part hereof, the single figure is a view in vertical section of an apparatus constructed in accordance with my invention and adapted to the practice of my new method.

The receptacle 1, here shown as a pot, is mounted in the furnace 2, fixed to any suitable support, such as legs 3. A carburizing medium 4, which may be a cyanide or a ferrocyanide or similar substance, is placed in the receptacle 1, which is heated by any suitable means, such as a gas burner 5. Vertically above receptacle 1 and in communication therewith, is a furnace chamber 6 having walls 7, and a heating element 8, preferably an electrical resistance element, is imbedded in walls 7. The furnace thus formed is adapted to heat the article to be treated to the proper hardening temperature.

An extension 9 is formed above wall 7 and has embedded therein a bracket 10 which holds a hook or similar member 11 adapted to carry an article 12 to be treated, here shown as a shaft. A door 13, hinged at 14, and having a handle 15, is provided to allow access to the furnace for the removal or insertion of various articles. A cover 16, which is generally of the bell type, has a cable 17 secured thereto and running over pulleys 18, the other end of said cable being attached to the door 13 at 110

point 19. A stack 20 is provided for withdrawing waste gases.

The upper portion 21 of the vertical furnace is provided with a tube or conduit 22 having a water jacket 23 surrounding it and being connected to a fan or blower 24, driven by any suitable means, such as a motor 25. An outlet pipe 26 leads from blower 24 into receptacle 1. If desired, an additional charging door 27 may be provided in the upper portion of the furnace.

An example of the operation of my device for case hardening is as follows:— Sodium cyanide is placed in receptacle 1 and heated by means of gas burner 5 to a temperature above its boiling point, about 800° C., the door of the furnace and the bell 16 both being closed and the fan 24 being in operation. An article to be treated is placed in furnace 6 and heated electrically by means of resistance element 8 to a temperature above the upper critical point, about 900° C. Cyanogen gases are produced by the volatilization and decomposition of the sodium cyanide and pass up into chamber 6, surrounding article 12, which is at such a high temperature that it rapidly absorbs the gases, case hardening the surface thereof. Unabsorbed gases pass upwardly, are drawn into conduit 22, and are cooled by water jacket 23 in order to prevent corrosion of the fan or blower member. The gases are then returned to receptacle 1 by blower 24 where they bubble through the liquid sodium cyanide, agitating the same, thus rendering the evolution of cyanogen gases more efficient and avoiding wasting any of the unabsorbed gases.

When it is desired to remove an article that has already been treated, it is not necessary to completely suspend the operation of the apparatus, but door 13 is opened, thereby removing cover 16 from the top of the furnace, inducing a draft through the furnace door opening and stack 20, removing the poisonous gases through the stack, thus obviating any danger to the operator. If desired, cover 16 may first be opened, blower 24 stopped, and then door 13 opened to charge or discharge the furnace.

My apparatus is very simple, the operation thereof does not require skilled workmen, and the coating produced on an article is uniform, the thickness thereof being a function solely of the time of exposure to the gases at any given temperature. The gas under pressure, coming in contact with the article to be case hardened, attacks the surface very vigorously, causing more rapid and deeper penetration. There is practically no danger of the poisonous gas escaping into the space around the apparatus since, if the pressure in the furnace becomes excessive, cover 16 will be unseated allowing the gases to enter the stack 20.

Although I have described my invention as embodied in a specific apparatus, it is to be understood that such description is intended to be illustrative only and does not limit my invention since it is obvious that various changes may be made within the scope thereof. For instance, instead of using a bracket to suspend articles to be treated, I may form a grid or series of grids in chamber 6 upon which various articles are placed, and I may use a different arrangement for allowing the escape of the poisonous gases when the operator opens the furnace door. Various other materials for carburizing may be used and I consider my invention as not limited to the use of sodium cyanide but various other materials, such as ferro- and ferri-cyanides and other gas producing carburizers, are also adapted for my purpose.

I claim as my invention:

1. A method of case hardening which comprises heating a cyanide to produce cyanogen gases, conducting said gases to an article or articles to be treated and returning the unabsorbed gases to their source.

2. A method of case hardening which comprises producing carburizing gases, conducting said gases to an article or articles to be treated and returning the unabsorbed gases to their source.

3. A method of case hardening which comprises heating a cyanide to produce cyanogen gases, allowing said gases to come in contact with an article to be treated, and agitating said cyanide.

4. A method of case hardening which comprises heating a cyanide to produce cyanogen gases, allowing said gases to come in contact with an article to be treated, and agitating said cyanide by bubbling unabsorbed gases therethrough.

5. An apparatus for case hardening comprising a furnace for heating an article to be treated, means for generating gases, means for allowing said gases to come in contact with said article, and a conduit for returning unabsorbed gases to the source of supply.

6. An apparatus for case hardening comprising a furnace for heating an article to be treated, means for generating gases, means for allowing said gases to come in contact with said article, and means for preventing escape of said gases into the space surrounding said apparatus.

7. An apparatus for case hardening comprising a furnace for heating an article to be treated, a receptacle adapted to hold gas-producing material, means for heating the same to generate gases, means for allowing said gases to come in contact with said article, and a conduit for returning unabsorbed gases to said receptacle.

8. An apparatus for case hardening com-

prising a vertical furnace, a receptacle furnace, a conduit in said top for leading adapted to hold gas-producing material at off said gases, and means for returning the the lower end thereof, means for heating same to said receptacle.

5 said receptacle to generate gases, means In testimony whereof, I have hereunto above said receptacle for holding an article subscribed my name this 30th day of November 1920.
to be treated, means for heating said article, WILLIAM J. MERTEN.
a removable cover closing the top of said
